UNITED STATES PATENT OFFICE

164,677

DECANTER BOTTLE

Ernest L. Du Pree, Old Greenwich, Conn., assignor to Schenley Industries, Inc., New York, N. Y., a corporation of Delaware

Application July 12, 1951, Serial No. 15,828

Term of patent 14 years

(Cl. D58—8)

To all whom it may concern:

Be it known that I, Ernest L. Du Pree, a citizen of the United States of America, residing at city of Old Greenwich, county of Fairfield, and State of Connecticut, have invented a new, original, and ornamental Design for a Decanter Bottle, of which the following is a specification, reference being had to the accompanying drawing, forming part thereof.

I claim:

The ornamental design for a decanter bottle, as shown.

ERNEST L. DU PREE.
